RAILWAY TRAFFIC CONTROLLING
APPARATUS

Charles H. Lay, Swissvale, Pa., assignor to The
Union Switch & Signal Company, Swissvale,
Pa., a corporation of Pennsylvania

Application February 9, 1937, Serial No. 124,856

8 Claims. (Cl. 246—3)

My invention relates to railway traffic controlling apparatus, and particularly to apparatus of the type involving a wayside signal and an associated train stopping device, both of which are controlled in part through the medium of a manually operable lever.

A feature of my invention is the provision of novel and improved means associated with a manually operable lever for establishing a visual indication to indicate whether or not the associated signal and train stopping device have responded to the movement of the lever. A further feature of my invention is the provision of novel and improved indication circuit means which is effective to provide two distinctive indications over a single line wire. A still further feature of my invention is the provision of indication circuit means for a control lever of an interlocking machine for establishing one visual indication which checks the stop positions of the controlled signal and train stopping device, and a second visual indication which checks the clear positions of such signal and train stopping device, and both of which visual indications are effected over the line circuit usually provided for the indication lock magnet of the lever. Other features and advantages of my invention will appear as the specification progresses.

I will describe three forms of apparatus embodying my invention, and will then point out the novel features thereof in claims.

In the accompanying drawings, Fig. 1 is a diagrammatic view of one form of apparatus embodying my invention where a visual indication at the lever of an interlocking machine is provided to check that both the train stopping device and the signal control relay have functioned to clear the wayside signal. Fig. 2 is a diagrammatic view of a second form of apparatus embodying my invention wherewith the stop positions of the train stops, as well as their clear positions, are checked. Fig. 3 is a diagrammatic view of still another form of apparatus embodying my invention wherewith only the clear positions of the train stops are checked.

In each of the three views, like reference characters designate similar parts.

Referring to Fig. 1, a stretch of railway track is provided with the usual insulated rail joints to form a track section $1T$, and within which section a track switch SW is located. The section $1T$ is provided with a track circuit including a source of current such as a battery 1 and a track relay $1TR$. The switch SW may be operatively connected with a power switch machine SM ,

which switch machine, in turn, may be controlled in any convenient manner, such as over a lever of an interlocking machine. The switch machine SM may be any one of the standard types and is shown conventionally only for the sake of simplicity. A switch circuit controller is connected with the switch SW as indicated by a dotted line, the arrangement being such that contacts $16-17$ and $20-21$ are closed when the switch is set at its normal position, and the contacts $18-19$ and $22-23$ are closed when the switch is moved to its reverse position.

A signal $2R$ governs eastbound traffic, that is, traffic moving from the left to the right in Fig. 1. Signals $2LA$ and $2LB$ govern westbound traffic over the switch SW . As here shown, these signals are of the color light type capable of displaying different lights to indicate different traffic conditions. In this instance, the signal $2R$ is provided with three lamps, the top lamp 54 of which when illuminated displays, according to usual practice, a green light, the center lamp 54 when illuminated displays a yellow light, and the bottom lamp 4 when illuminated displays a red light, display of either lamp 54 or 4 being a signal for a train to proceed, and the display of the lamp 4 being a stop signal. The signals $2LA$ and $2LB$ are each provided with two lamps, the top lamp in each case being a proceed signal and the bottom lamp being a stop signal. It will be understood that my invention is not limited to this one form of wayside signals, and other forms of wayside signals may be used, if desired.

Train stopping devices $2RV$, $2LAV$ and $2LBV$ are associated with the signals $2R$, $2LA$ and $2LB$, respectively. These train stopping devices may be any one of several different forms, among them being the electropneumatic trip arm type, such as disclosed and claimed in the United States Letters Patent No. 1,775,811, granted September 16, 1930, to John P. Coleman, for Railway traffic controlling apparatus. It is deemed sufficient for the present application to point out that these train stopping devices are biased to an active or train stopping position where their trip arm cooperates with train carried apparatus for causing an automatic application of the train brakes. When current is supplied to the controlling element of the train stopping device, the device is operated to a clear position where its trip arm is lowered and engagement with the train carried apparatus is avoided. Each train stopping device has operatively connected therewith a circuit controller operative to two different positions corresponding to the two positions of the device. For

example, the contact members 5 and 6 of the controller for the train stop 2RV occupy a vertical position, as viewed in the drawings, when the device 2RV is set at its stop position, and 5 are operated to a horizontal position when the device 2RV is lowered to its non-stopping or clear position.

Each wayside signal and the associated train stop are governed by a control relay designated 10 by the reference character H, plus a prefix corresponding to the signal. These control relays are, in turn, governed by a lever 2, which may be, for example, one of a number of such levers of an interlocking machine located at a point 15 remote from the track section 1T, such as in an interlocking tower. The lever 2 is capable of assuming a plurality of different positions indicated by broken lines in the drawings, and designated by the reference characters L, B, N, D and R. The 20 center position N is the normal position of lever 2, and the lever is operated to its extreme right-hand position R for controlling the relay 2RH associated with the eastbound signal 2R, and is operated to its extreme left-hand position L to 25 control the relays 2LAH and 2LBH associated with the west-bound signals 2LA and 2LB, respectively. The positions B and D are the usual indication positions for such signal control levers of an interlocking machine. Operatively connected with the lever 2 are four controller contact members 8, 9, 10 and 11, together with a locking segment 12. It will be understood, of course, that lever 2 is connected with the usual mechanical interlocking provided for such in- 30 terlocking machines. With the lever 2 moved to its R position, closing contact 8-70, a circuit is completed from the BX terminal of any convenient source of current, such as a battery not shown, over contact 8-70, traffic controlled circuit network 13, line wire 130, winding of relay 2RH, and to the CX terminal of the current source. Hence, movement of the lever 2 to its R position is effective to energize the signal control relay 2RH to pick up that relay. Moving lever 2 to its L position is effective to complete a 40 circuit for either the relay 2LAH or the relay 2LBH, according to the position of the switch SW. This circuit may be traced from the BX terminal over contact 8-71, traffic controlled circuit network 14, line wire 15, contact 16-17 when the switch is set at its normal position, winding of relay 2LAH, and to the CX terminal; and the circuit extends from the line wire 15 over contact 18-19 when the switch is moved to its reverse position, winding of relay 2LBH, and to the CX terminal. The traffic control circuit networks 13 and 14 would include contacts of the track relay 1TR and contacts controlled by traffic conditions to each side of the section 1T in accordance with the usual practice, such circuit networks being omitted from the drawings for the sake of simplicity, since they form no part of my present invention.

The operating circuits for the signals and the train stops will be described only in so far as they are controlled by the associated control relays. That is, the operating circuits for the signals and train stops will be described only in so far as is necessary for a complete understanding of my invention, and it will be understood that these operating circuits may be controlled by traffic controlled apparatus as desired, in addition to the control effected by the control relays. It will also be understood that the usual holding circuits for the train stops are provided.

Looking at signal 2R, the lamp 4 is illuminated over two simple operating circuits, one of which includes contact 5 of the controller for train stop 2RV in the stop position, and the other of which includes contact 5-33 of the controller for the train stop 2RV in the clear position and back contact 31 of the relay 2RH. With relay 2RH picked up, closing front contact 32, an operating circuit for the train stop 2RV is completed. This operating circuit includes the BX terminal, front contact 32 of relay 2RH, wire 131, control element of train stop 2RV and to the CX terminal, the trip arm and the associated controller contacts being thereby moved to their clear positions. Since it is desirable when a train stop is cleared 15 for a train to pass to also lower the trip arm of the opposing train stop, the operating circuit for train stop 2RV is provided with a branch circuit to train stop 2LAV when the switch SW is normal and to train stop 2LBV when the switch is re- 20 versed. With the switch normal, this branch circuit extends from wire 131 over contact 20-21, control element of train stop 2LAV and to the CX terminal; and with the switch reversed it extends from wire 131 over contact 22-23, control element of train stop 2LBV and to the CX terminal. 25 With the relay 2RH picked up and the train stop 2RV lowered to the clear position, an operating circuit is completed for illuminating lamp 54 or lamp 1 of signal 2R, the lamp selected being in 30 accordance with the position of an associated line relay 2RD. The line relay 2RD is governed over a line circuit not shown, which would be controlled by traffic conditions to the right of signal 2R in accordance with usual practice. The 35 operating circuit for lamps 54 and 1 may be traced from BX terminal, contact 5-33 of the controller of train stop 2RV, front contact 35 of relay 2RH, front contact 56 of relay 2RD, lamp 54 and to the CX terminal, or if the relay 2RD 40 is released the circuit includes back contact 55 of relay 2RD, lamp 1 and to the CX terminal. It follows that normally the stop lamp 4 of signal 2R is illuminated and train stop 2RV is raised to the stop position, but that movement of lever 2 45 to the R position energizes relay 2RH, and that relay on picking up causes first the train stop 2RV along with the opposing train stop to be lowered, and when both relay 2RH and train stop 2RV have functioned either the lamp 54 or lamp 50 1 of signal 2R, according to the position of the line relay 2RD, is illuminated to display a proceed signal.

The stop lamp 66 of signal 2LA is illuminated over two operating circuits, one of which includes contact 38 of the controller for the train stop 2LAV in the stop position, and the other of which includes BX terminal, contact 38-39 closed when the train stop 2LAV is lowered, wire 121, back contact 68 of relay 2LAH, wire 122, 60 lamp 66 and to the CX terminal. With relay 2LAH picked up, closing front contact 36, an operating circuit is formed for the associated train stop 2LAV and also for the opposing train stop 2RV. Starting from the BX terminal, this circuit includes front contact 36 of relay 2LAH, wires 132 and 131, contact 20-21, control element of train stop 2LAV and to the CX terminal; and a branch path from wire 131 through the control element of train stop 2RV to the CX 70 terminal. When the train stop 2LAV is cleared in response to relay 2LAH picked up, the proceed lamp 37 of signal 2LA is illuminated over an operating circuit including BX terminal, controller contact 38-39, wire 121, front contact 40 75

of relay 2LAH, wire 123, lamp 37 and to the CX terminal.

The stop lamp 67 of signal 2LB is likewise provided with two operating circuits, one of which includes the contact 42 of the controller for the train stop 2LBV at the stop position, and the other of which includes the controller contact 42-43 closed when the train stop is cleared, wire 124, back contact 69 of relay 2LBH and wire 125. With the relay 2LBH picked up, closing front contact 41, the associated train stop 2LBV and the opposing train stop 2RV are cleared since relay 2LBH is selected only when switch SW is reversed. The operating circuit for the train stops now consists of BX terminal, front contact 41 of relay 2LBH, wires 133 and 131, contact 22-23 closed with the switch reversed, control element of train stop 2LBV and to the CX terminal; and from wire 131 branching 20 through the control element of train stop 2RV and to the CX terminal. With both relay 2LBH picked up and the train stop 2LBV cleared, the proceed lamp 45 of signal 2LB is illuminated over the circuit from BX terminal, controller contact 42-43, wire 124, front contact 44 of relay 2LBH, wire 134, lamp 45 and to the CX terminal. Thus movement of the lever 2 to its L position selects either the relay 2LAH or 2LBH, according to the position of the switch, and the selected relay on picking up completes operating circuits for first clearing the associated train stop and then clearing the associated signal, it being necessary that the train stop occupies its clear position as well as the control relay being picked up in order that the proper proceed signal lamp may be illuminated.

The locking segment 12 attached to lever 2 cooperates with a latch 24 operated by an indication magnet 2M. When the operator moves the lever 2 back toward the N position from either the R or the L position, the latch 24 engages either notch 25 or 26 in the segment 12 at the D and B positions, respectively, and prevents movement of the lever to the normal position N until the indication magnet 2M is energized to lift the latch 24. The magnet 2M is provided with the usual indication circuit which, in accordance with the usual practice, is closed only when all of the signals are set at the stop positions. In this instance, such indication circuit may be traced from the BX terminal of the current source over back contacts 27, 28 and 29 of relays 2LAH, 2LBH and 2RH, respectively, indication line wire 30, controller contact 11-76 or 11-78 closed in the D and B positions of lever 2, respectively, winding of magnet 2M, and to the CX terminal. It will be understood, of course, that this indication circuit is completed over the usual common return line wire. It follows that lever 2 moved to either its R or L position can be returned to its normal position N to release the usual interlocking associated with the lever 2 only in the event that each of the signal control relays is released to establish the stop positions of the respective signals and train stops.

For establishing a visual indication to indicate whether or not the proper signal and train stop have been operated to the clear position in response to a movement of the lever 2 to its R or L position, I provide indication apparatus which is associated with the usual indication circuit described hereinbefore whereby a visual indication is effected without additional line wires. It is believed that this indication appa-

ratus embodying my invention can best be understood by a description of the operation of the apparatus of Fig. 1.

I shall first assume that lever 2 is moved to the R position to energize the control relay 2RH for clearing the train stop 2RV and the signal 2R. With relay 2RH picked up, closing front contacts 32 and 35, the train stop 2RV is first operated to its clear position along with the opposing train stop 2LAV, and then, over the closed position of the controller contact 5-33 and the front contact 35 of relay 2RH, the signal 2R is cleared, the lamp 1 being illuminated in the event the line relay 2RD is released, closing back contact 55, and the lamp 54 being illuminated if the relay 2RD is picked up, closing front contact 56. The closing of controller contact 6-34, in response to the clearing of the train stop 2RV, completes an indication circuit by which current flows from the BX terminal adjacent the lever 2 over controller contact 9-72 closed in the R position of the lever, winding of an indication relay 2LP, indication line wire 30, front contact 46 of relay 2RH, contact 6-34, and to the CX terminal of the current source, and the relay 2LP is energized. Relay 2LP on picking up, closing front contact 47, completes a simple circuit for an indicating lamp 2K, which is preferably mounted just above or below the lever 2 so as to be plainly visible to the operator. Consequently, the lamp 2K is illuminated to indicate that both the train stop 2RV and the relay 2RH have functioned to clear the signal 2R.

Assuming next that the lever 2 is operated from the N position to the L position and the control relay 2LAH is selected, the train stop 2LAV is operated to its clear position and the lamp 37 of signal 2LA is illuminated, the operating circuits being controlled by the relay 2LAH in the manner described hereinbefore. Closing the controller contact 49-50 of the train stop 2LAV completes an indication circuit by which current flows from the BX terminal at the lever over contact 9-73, winding of relay 2LP, indication line wire 30, back contacts 29 and 28 of relays 2RH and 2LBH, respectively, front contact 48 of relay 2LAH, wire 128, controller contact 49-50, and to the CX terminal, and relay 2LP is energized to effect the illumination of the lamp 2K. In the event the switch SW is reversed at the time the lever 2 is moved to its L position and the relay 2LBH is selected, the train stop 2LBV is cleared and the lamp 45 of signal 2LB is illuminated over operating circuits controlled by relay 2LBH, as heretofore described. An indication circuit now extends from the BX terminal at the lever 2 up to the back contact 29 of relay 2RH, as previously traced, and thence over front contact 51 of relay 2LBH, wire 129, controller contact 52-53 of train stop 2LBV, and to the CX terminal, and relay 2LP is energized, and the lamp 2K is illuminated to indicate that both the train stop 2LBV and relay 2LBH have functioned to clear the signal 2LB.

When the relay 2RH, or 2LAH, or 2LBH is released, subsequent to having been energized to clear the corresponding signal and train stop, and the lever 2 placed at its D or B position, and the usual indication circuit for the lock magnet 2M is completed, current also flows from the line wire 30 through winding of indication relay 2LP, contact 10-74 or 10-75 according to the indication position of lever 2, and thence to the CX terminal, with the result that relay 2LP is energized and the lamp 2K is illuminated in addition to the energizing of the lock magnet 2M.

It is to be seen, therefore, that movement of the lever 2 to either the R or L position for selecting a control relay is followed by the illumination of the lamp 2K, in the event the proper control relay is picked up and the associated train stop is moved to the clear position. Furthermore, the lamp 2K is illuminated when the lever 2 is moved to one of its indication positions, in the event all the control relays are properly released for setting the associated signals and train stops at their stop positions. It is to be noted that, when the lever 2 is moved to the R or L position to clear a train stop and signal, current flows from the BX terminal adjacent the lever 2 over the indication line wire 30 and to the CX terminal of the current source adjacent the wayside apparatus, whereas, when the control relays are released to restore the signals and train stops to their respective stop positions, current flows from the BX terminal adjacent the wayside apparatus over the indication line wire 30 to the CX terminal adjacent the lever. That is to say, two indication circuits are effected over one control wire by reversing the connections to the current source at each end.

In the form of the invention disclosed in Fig. 2, the apparatus of Fig. 1 is modified, as required, to effect two different visual indications for the stop and clear positions of the train stops and signals, two indicating lamps being provided in place of one lamp governed by a relay.

In Fig. 2, the track layout is the same as in Fig. 1. At the tower the lever 2 and the contacts operated thereby are the same as in Fig. 1, but the connection to the indication magnet 2M is controlled over three branch paths, one of which includes back contact 1TR of the track relay 1TR, a second path includes a contact 1TE of a time element device usually provided for such lever, and a third path includes an approach locking contact 2AR that would be associated with the approach locking of the signal 2R in the usual manner. Furthermore, two lamps 2HK and 2MK are mounted preferably just above or below the lever 2, to be plainly visible to the operator. The lamp 2HK is used to indicate the clear position of the signals and train stops controlled by lever 2, and the lamp 2MK is illuminated to indicate the stop position of the signals and train stops, the two lamps being of the same color or of different colors, as desired.

In describing the operation of the apparatus of Fig. 2, I shall assume that lever 2 is moved from the N position to the R position to energize relay 2RH for clearing the associated train stop 2RV and signal 2R. The control circuit for relay 2RH is completed at the contact 8-70 of lever 2, the same as described for Fig. 1, and relay 2RH on picking up, closing front contact 32, completes the operating circuit for the train stops whereby the stop 2RV, along with the opposing train stop 2LAV, are lowered to their clear positions. Train stop 2RV on being operated to the clear position, closing contact 5-33, completes the operating circuit for clearing the signal 2R, the lamp 1 being illuminated if the line relay 2RD is released, closing back contact 55, and the lamp 54 being illuminated if the line relay 2RD is picked up, closing front contact 56. Closing controller contact 6-34 of the train stop 2RV completes an indication circuit that includes the BX terminal of the current source, lamp 2HK, controller contact 9-72, indication line wire 30, front contact 46 of relay 2RH, contact 6-34, and to the CX terminal; and the lamp 2HK is illuminated to indicate

that the train stop 2RV and the relay 2RH have both functioned to clear the signal 2R.

When the relay 2RH is released to restore signal 2R and train stop 2RV to their stop positions and lever 2 is returned to its D position, an indication circuit is completed from the BX terminal at the wayside apparatus over the stop position of a controller contact 57 of train stop 2LAV, wire 126, back contact 58 of relay 2LAH, wire 59, controller contact 60 of train stop 2LBV in the stop position, wire 61, back contact 62 of relay 2LBH, wire 63, controller contact 64 of train stop 2RV in the stop position, back contact 65 of relay 2RH, indication line wire 30, contact 10-74 of the lever controller closed in the D position of the lever, wire 127, lamp 2MK, and to the CX terminal, and the lamp 2MK is illuminated. Branching from the wire 127 is a connection to the winding of magnet 2M over either the back contact 1TR or the time element contact 1TE, winding of magnet 2M, and to the CX terminal. The third path for the magnet 2M is also completed over controller contact 11-76 and the approach locking contact 2AR. Hence, a visual indication is displayed by the lamp 2MK when the usual indication circuit for the lock magnet 2M is closed in response to the restoring of the train stops and associated signals to their stop positions.

In the event the lever 2 is moved to the L position to energize relay 2LAH for clearing the associated train stop 2LAV and associated signal 2LA, the lamp 2HK is illuminated over an indication circuit extending from BX terminal, lamp 2HK, contact 9-73, indication line wire 30, back contacts 65 and 88 of relays 2RH and 2LBH, respectively, front contact 48 of relay 2LAH, wire 128, controller contact 49-50 of train stop 2LAV, and to the CX terminal. If the switch is reversed and the relay 2LBH is selected in response to lever 2 being moved to the L position and the train stop 2LBV and the signal 2LB are cleared over the operating circuits previously described, the lamp 2HK is illuminated over an indication circuit the same as before traced up to back contact 65 of relay 2RH, and thence over front contact 51 of relay 2LBH, wire 129, controller contact 52-53 of train stop 2LBV, and to the CX terminal. In each case, the lamp 2HK indicates the clear position of the train stop and that the proper control relay is picked up to clear the desired signal. The lamp 2MK is illuminated each time the usual indication circuit for the magnet 2M is completed, and which indication circuit checks the stop position of each of the train stops as well as the released position of each of the associated control relays.

In Fig. 3, the adjacent ends of two track sections 2T and 3T of a stretch of railway track are illustrated. Two opposing signals 3R and 3L are located at the junction of sections 2T and 3T. In this instance, the signal 3R is equipped with a red lamp 81 and a yellow lamp 82, and the signal 3L is provided with two color light units 3LA and 3LB, the unit 3LA being equipped with a red lamp 83 and a yellow lamp 84 as well as a green lamp 85, and the unit 3LB being equipped with a red lamp 86 and a yellow lamp 87. The lamp 87 provides the usual "calling on" signal.

Two train stops 3RV and 3LV are associated with the signals 3R and 3L, respectively. Since these two train stops are adjacently located, the two respective trip arms may be operated by the

same control unit, or two separate units may be provided.

The signals 3R and 3L and the associated train stops are governed by three control relays 3RH, 3LAH and 3LBH, together with a line relay 3LAD. 5 These control relays are, in turn, governed through the medium of a lever 3 of an interlocking machine, and which lever is preferably similar in construction to the lever 2 of Figs. 1 and 2. The line relay 3LAD is governed over a line circuit not shown, and which line circuit would be controlled by traffic conditions to the left of signal 3L in accordance with the usual practice.

In accordance with my invention, lever 3 is provided with an indication relay 3LP and an indication lamp 3K, as well as the usual indication lock magnet 3M.

It is thought that the apparatus of Fig. 3 may best be understood by a description of its operation. Normally, that is, when lever 3 is at its N position and the control relays 3RH, 3LAH and 3LBH are deenergized and the associated train stops are set at their stop positions, the red lamp 81 if signal 3R is illuminated over a simple circuit including back contact 88 of relay 3RH, and the red lamps 83 and 86 of signal 3L are illuminated over a simple circuit including back contact 89 of relay 3LAH. Movement of lever 3 to its R position, closing the controller contact 90-91, 10 completes a control circuit for energizing the relay 3RH, and that relay on picking up, closing front contact 92, in turn, completes the operating circuit easily traced for the two train stop devices 3RV and 3LV, in parallel. The red lamp 81 is now 15 extinguished and the yellow lamp 82 of the signal 3R is illuminated over an operating circuit extending from the BX terminal of the current source through controller contact 93 of train stop 3RV when moved to its clear position, controller contact 94 of train stop 3LV when moved to its 20 clear position, front contact 95 of relay 3RH, lamp 82, and to the CX terminal of the current source. In response to the clearing of the two train stops 3RV and 3LV, indication current flows 25 from the BX terminal adjacent the lever 3 over winding of relay 3LP, controller contact 96-97 of lever 3, indication line wire 98, back contacts 99, 100 and 101 of relays 3LBH, 3LAH and 3LAD, respectively, front contact 102 of relay 3RH, controller contact 103 of train stop 3RV in its clear 30 position, and to the CX terminal; and the indication relay 3LP is picked up, completing through front contact 104 a circuit for illuminating the lamp 3K. Hence, the lamp 3K is illuminated if 35 the train stop 3RV is operated to its clear position, and the relay 3RH is picked up, the other relays remaining released.

With lever 3 moved to its L position, closing controller contact 90-105, the relay 3LAH is 40 selected; and that relay on picking up, closing front contact 106, completes the operating circuits for the train stops, which, on being operated to their clear positions, complete an operating circuit for clearing the signal 3L. This 45 operating circuit for the signal 3L includes the BX terminal, controller contact 93 in the clear position, controller contact 94 in the clear position, front contact 107 of relay 3LAH, back contact 108 of line relay 3LAD, lamp 84, and to the CX terminal; or, it includes front contact 109 50 and the lamp 85 of signal 3L, in the event the line relay 3LAD is picked up. It is to be observed that, when relay 3LAH is picked up opening back contact 89, both red lamps 83 and 86 are extinguished. This time the relay 3LP is energized 55

over controller contact 96-110, indication line wire 98, back contact 99 of relay 3LBH, front contact 111 of relay 3LAH, and a controller contact 112 of the train stop 3LV in the clear position. Hence, the relay 3LP is picked up and the lamp 3K is illuminated in response to movement of the lever 3 to its L position, in the event the control relay 3LAH is picked up and the train stop 3LV is operated to the clear position. 60

The relay 3LBH is selected by virtue of movement of lever 3 to its L position and the depressing of a push button PB to close a contact 113. Relay 3LBH on picking up, closing front contact 114, completes the operating circuit for the train stops 3RV and 3LV. The lamp 87 of signal 3L is 15 now illuminated over the previously traced circuit, including controller contacts 93 and 94 each in the clear position, and thence over front contact 115 of relay 3LBH. The indication relay 3LP receives current over the circuit previously traced 20 up to indication line wire 98, and thence over front contact 116 of relay 3LBH and the controller contact 112 in the clear position. Again, the lamp 3K is illuminated in response to movement of lever 3 to an L position if the relay 3LBH 25 is picked up to clear the train stops and the "calling on" signal 87, and if the train stop 3LV is operated to its clear position. It is to be observed that, when relay 3LBH is picked up to display the "calling on" lamp 87, both red lamps 83 30 and 86 remain illuminated.

The usual indication circuit for the magnet 3M of Fig. 3 may be traced from the BX terminal at the wayside apparatus over back contacts 117, 101, 100 and 99 of the relays 3RH, 3LAD, 3LAH 35 and 3LBH, respectively, indication wire 98, controller contact 118 in either the B or D position, the usual circuit network 119, winding of magnet 3M, and to the CX terminal. It follows that the lamp 3K is illuminated to check the clear position 40 of the train stops and the energized position of the selected control relay associated with the lever 3.

Although I have herein shown and described only three forms of apparatus embodying my invention, it is understood that various changes and modifications may be made therein within the scope of the appended claims without departing from the spirit and scope of my invention. 45

Having thus described my invention, what I 50 claim is:

1. In combination, a railway signal, a relay for governing said signal and effective when energized to establish a proceed indication for the signal and when released to establish a stop indication for the signal, a manually operable lever for controlling said relay and having an operated position and an indication position as well as a normal position; a first indication circuit including a magnet, a contact closed at the indication 55 position of the lever, a particular line wire and a back contact of the relay; a second indication circuit including a front contact of the relay, said line wire, a contact closed at the operated position of the lever, and an indicating lamp; and a current source having its positive terminal connected to said back contact of the first indication circuit and to a terminal of the lamp of the second indication circuit and having its negative terminal connected to a terminal of the magnet 60 of said first circuit and to said front contact of the second circuit.

2. In combination, a railway signal, a relay for governing said signal and effective when energized to establish a proceed indication for the 65

signal and when released to establish a stop indication for the signal, a manually operable lever for controlling said relay and having an operated position and an indication position as well as a 5 normal position, a control circuit including a contact closed at the operated position of the lever and a winding of the relay to energize the relay; a first indication circuit including an indicating device, a contact closed at the indication 10 position of the lever, a back contact of the relay and a current source, the positive and negative terminals of the source being connected with said indication circuit adjacent the relay contact and the indicating device respectively; and a second 15 indication circuit including a front contact of the relay, another indicating device, a contact closed at the operated position of the lever and said current source, the positive and negative terminals of the source being connected with said 20 second indication circuit adjacent the lever contact and the relay contact respectively.

3. In combination, a railway signal, a control relay for governing said signal and effective when energized to establish a proceed indication for the 25 signal and when released to establish a stop indication for the signal, a control lever for controlling said relay and having a reverse position and an indication position, a magnet associated with the lever for governing its movement, an 30 indicating means associated with the lever and effective when energized to display a visual indication, a control circuit including a contact closed at the reverse position of the lever and a winding of the control relay to energize said relay; a first indication circuit extending from the 35 positive terminal of a current source over a back contact of the control relay, a line wire, a contact closed at the indication position of the lever, a winding of said magnet and the negative terminal 40 of said source; and a second indication circuit extending from the positive terminal of said source over a control element of said indicating means, a contact closed at the reverse position of the lever, said line wire, a front contact of the 45 relay and the negative terminal of said source.

4. In combination, a railway signal having a proceed signal lamp, a train stop having a stop position and a clear position, a relay, a first operating circuit for operating said train stop to its clear position and including a front contact 50 of the relay, a second operating circuit to illuminate said signal lamp and serially including a contact closed by the train stop in the clear position and a front contact of the relay, a manually operable lever having an operated position 55 and another position, indication means associated with the lever, a control circuit for energizing said relay and including a contact closed at the operated position of the lever; a first indication circuit extending from the positive terminal of a current source over a control element of the indication means, a contact closed at the 60 operated position of the lever, a line wire, a front contact of the relay, a contact closed at the clear position of the train stop and the negative terminal of the source; and a second indication circuit extending from the positive terminal of said source over a contact closed at the stop position 65 of the train stop, a back contact of the relay, said line wire, a contact closed at said other position of the lever, a control element of said indication means and the negative terminal of the source.

5. In combination, a train stop capable of 70 operation to a stop position and to a non-stop-

ping position, a relay for governing said train stop and effective when energized to establish said non-stopping position of the train stop and when released to establish the stop position of the train stop, a manually operable lever having an operated position and an indication position as well as a normal position, an indication magnet for governing the movement of said lever, a first and a second indicating lamp associated with said lever, a control circuit including an operated position contact of the lever and a winding of 10 said relay for energizing the relay; a first indication circuit extending from the positive terminal of a current source over said first lamp, an operated position contact of the lever, a line wire, 15 a front contact of the relay, a contact closed at the non-stopping position of the train stop and the negative terminal of the source; and a second indication circuit extending from the positive terminal of said source over a contact 20 closed at the stop position of the train stop, a back contact of the relay, said line wire and two branch paths to the negative terminal of the source one path comprising an indication position contact of the lever and a winding of said 25 magnet and the second path comprising an indication position contact of the lever and said second lamp.

6. In combination, a railway signal positioned at a location along a track, a relay located at said signal for governing the signal and effective when energized to establish a proceed indication for the signal and when released to establish a stop indication for the signal, a manually operable lever located at a tower remote from the signal 30 and provided with an operated position and an indication position, a current source provided with a positive terminal and a negative terminal at both the tower and at the signal, a first and a second indication device located at the tower, 35 a control circuit including a contact closed at the operated position of the lever and a winding of the relay for energizing the relay; a first indication circuit including an energizing element of 40 said first indication device, a contact closed at the indication position of the lever, a line wire and a back contact of said relay and said first indication circuit connected with the positive terminal at the signal and with the negative terminal at the tower; and a second indication circuit including an energizing element of said second 45 indication device, a contact closed at the operated position of the lever, said line wire and a front contact of the relay and said second indication circuit connected with the positive terminal at the tower and with the negative terminal at the signal. 50

7. In combination, a railway signal positioned at a location along a track, a relay located at said signal for governing the signal and effective when energized to establish a proceed indication for the signal and when released to establish a stop indication for the signal, a manually operable lever located at a tower remote from the signal, 60 said lever provided with an operated position and an indication position, a current source provided with a positive terminal and a negative terminal at both the tower and at the signal, a control circuit including a contact closed at the operated position of the lever and a winding of the relay to energize the relay, an indication magnet for governing the movement of said lever, 65 other indication means located at said tower for displaying a visual indication; a first indication circuit extending from the positive terminal at the tower and with the negative terminal at the signal. 70

5 minal adjacent the signal location over a line wire to the negative terminal at the tower and having interposed therein a back contact of said relay, a contact closed at the indication position of the lever and a winding of said magnet; and a second indication circuit extending from the positive terminal at the tower over said line wire to the negative terminal adjacent the signal and having interposed therein a contact closed at 10 the indication position of the lever, an energizing element of said other indication means, and front contact of the relay.

15 8. In combination, a railway signal located along a track and having a proceed signal lamp, a train stop associated with said signal having a stop position and a clear position, a relay, a first operating circuit for operating said train stop to its clear position and including a front contact of the relay, a second operating circuit 20 to illuminate said signal lamp and serially including a contact closed by the train stop in the clear position and a front contact of the relay, a manually operable lever located at a tower remote from the signal and having an operated

position and an indication position, a current source provided with a positive terminal and a negative terminal at both the tower and at the signal, a first and a second indication means located at the tower, a control circuit for energizing the relay including a contact closed at the operated position of the lever; a first indication circuit including an energizing element of said first indication means, a contact closed at the indication position of the lever, a line wire and a back contact of said relay and said first indication circuit connected with the positive terminal at the signal and with the negative terminal at the tower; and a second indication circuit including an energizing element of said second indication means, a contact closed at the operated position of the lever, said line wire, a front contact of said relay and a contact closed at the clear position of the train stop and said second indication circuit connected with the positive terminal at the tower and with the negative terminal at the signal. 20

CHARLES H. LAY.
